UNITED STATES PATENT OFFICE.

LADISLAUS DE DOORY, OF NEW YORK, N. Y.

DESIGN FOR A SHIRT BOARD.

Application filed February 6, 1926. Serial No. 16,419. Term of patent 3½ years.

To all whom it may concern:

Be it known that I, LADISLAUS DE DOORY, a subject of the Kingdom of Hungary, and a resident of the borough of Manhattan, city, county, and State of New York, have invented a new, original, and ornamental Design for a Shirt Board, of which the following description, in connection with the accompanying drawing, is a specification.

Referring to the drawing:

Fig. 1 is a plan view; and
Fig. 2 is an edge view of a shirt board showing my new design.

I claim as my invention:

The ornamental design for a shirt board, substantially as shown.

LADISLAUS DE DOORY.
